UNITED STATES PATENT OFFICE.

ARTHUR R. KONSALIK, OF PHILADELPHIA, PENNSYLVANIA.

SKYLIGHT.

Application filed December 31, 1923. Serial No. 683,540.

To all whom it may concern:

Be it known that I, ARTHUR R. KONSALIK, citizen of the United States, residing at Philadelphia, in the county of Philadelphia, 5 State of Pennsylvania, have invented certain new and useful Improvements in Skylights, of which the following is a specification.

The object of my invention is a novel skylight for building structures such as theatres, factories and the like; which may be mechanically operated for ventilating purposes; and automatically operated in case of an emergency such as fire, so as to permit 10 the escape of smoke and fumes.

Another object of my invention is a skylight of such construction that it may be operated more easily and with less effort than skylights heretofore in use.

With these and other objects in view, my invention consists of certain novel features of construction to be hereinafter more fully described, and illustrated in the appended drawings; of which—

Fig. 1, is an elevation of a roof structure with its skylights embodying my invention.

Fig. 2, is a sectional view of a line 2—2 of Fig. 1 showing the skylight operating means.

Fig. 3, is a section on line 3—3 of Fig. 2, showing the means for the simultaneous operation of a plurality of skylights.

Fig. 4, is a sectional view on line 4—4 of Fig. 3 showing the pivotal means used to secure the covers to the jambs, and

Fig. 5, is a sectional view on line 5—5 of Fig. 4 showing details of construction.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawings, each sky-

light 1 consists of an inclined frame or jamb structure 2, and a cover therefor made up of two wings 3 and 4 respectively, hingedly secured to the jamb by means of inclined pins or pintles 5, which are at such an angle to the horizontal plane as to tend to open the skylight by a fraction of the weight of the cover only. This has the decided advantage over a horizontally pivoted cover, in so far as only a fraction of the weight of the cover must be opposed in closing the skylight; whereas in a horizontally pivoted cover the full weight of the cover must be raised in order to bring the same into closed position.

Attached to each wing of the cover is the flexible connection 6 which leads to the cable 7 which after passing around an idle pulley 8 located on the side of the framework opposed to the skylight, is secured 65 through the adjustable turn-knuckle 9 to the central ring 10. Through this ring 10 all the skylight covers are operated simultaneously by means of the single cable 11 which winds up on a drum, not shown, operated by 70 means of the worm 12 and gear 13 which may be situated somewhere along the wall of the building or at any other point so as to be easily accessible.

Between the cable 11 and ring 10 there is 75 interposed a fusible link 14 for the purpose of automatically releasing all the skylight covers simultaneously in the event of fire.

The T member 15 of the jamb so overlaps and engages with the edges of the two wings 3 and 4 as to make a tight joint when the covers are in a closed position, said T members being centrally positioned and receiving the juxtaposed inturned edges of 80 the cover sections when the latter are closed as seen in Figure 5.

The pintles 5 are supported at their ends in bearings 16 and 17 located in the base member 18 and upper member 19 respectively, said bearings being so positioned relative to each other, as to throw the upper end of the pintle 5 out of vertical alignment with the lower end, thus inclining the same.

100

It will be noted that the mechanical operation of both closing and opening the skylights is made considerably easier by the angularly pivoted covers, while an equally rapid, automatic release of the covers is obtained through the fusible link as in skylights employing horizontally pivoted covers.

I am aware of the patent to Goldman No. 1,009,502 wherein the covers are shown as swinging downwardly on horizontal pintles, but my invention is differentiated therefrom since my covers swing laterally upon inclined pintles, and in addition my covers are made in two parts or sections, which facilitates and expedites the automatic or manual operation thereof, and to none of the devices of the prior art do, I herein make my claim.

20 I preferably locate the manually operated mechanism for the cable 11 comprising parts seen at the lower right hand portion of Fig. 2, down stairs on the floor so that in case of fire an attendant can readily cut the cable. 25 11. I desire to also call especial attention to the feature of the sectional covers comprising wings 3 and 4 since it will be apparent that in the case of lateral movable wings such as I employ in case of fire, the firemen 30 can shut one of the wings, as the wing 4, and allow the other wing, as 3, seen in Fig. 5, to stand open, and through this open space he can insert his hose for the purpose of putting out the fire. These are practical features of very great importance in practice and are present in no other construction with which I am familiar.

Having thus described my invention, what I claim as new and desire to secure by 40 Letters Patent, is:

1. A skylight construction of the character stated, comprising a supporting structure having a vertically disposed wall, a frame projected therefrom including a 45 downwardly sloping top and vertical sides, the outer edges of which sides incline from the juncture of the frame with said wall upwardly and outwardly, pintles inclined upwardly and outwardly and arranged at the 50 frame outer corners in parallelism with the said inclined edges, an outwardly opening laterally movable cover section carried by each pintle each cover section having an inner inwardly deflected flange, a central, 55 substantially T-shaped outwardly inclined member for said frame, positioned centrally of said inclined pintles, against which central member, the inner flanged terminals of each cover section abut in closed position 60 and means common to each cover section for maintaining the latter in closed position.

2. In a skylight of the character stated, a supporting structure having a frame provided with a top and vertical sides, whose

outer edges incline upwardly and outwardly, oppositely located pintles inclined upwardly and outwardly and arranged at opposite outer corners of said frame, and having their top and bottom ends mounted therein, a laterally movable cover section 70 carried by each pintle, said cover sections having their inner edges provided with inwardly deflected terminal flanges, an outwardly and upwardly inclined T-shaped member carried by said frame and positioned centrally of said pintles, and having its side flanges adapted to receive said inner inwardly deflected cover flanges, when closed, the central web of said T shaped member being located intermediately of the 80 terminal flanges of said cover sections when closed, a pulley oppositely located to said pair of cover sections, a ring below said pulley, a connection having one end secured to said cover sections, and its other end 85 passed over said pulley and secured to said ring, another connection leading from said ring, and a fusible link in said connection.

3. In a device of the character stated, a supporting structure, having side walls, an inclined top and an inclined base member, oppositely located inclined pintles having their upper ends passing through said inclined top and their lower ends positioned within said base member, said pintles inclining outwardly and upwardly from the vertical, a pair of laterally swinging cover sections mounted at their outer ends to turn laterally on said inclined pintles, the inner terminal edge of each cover section having an inturned flange, an outwardly inclined T shaped member, centrally located between said pintles and having the same degree of inclination as said pintles, the central web of said member being parallel to said in-turned flanges, when said cover sections are closed, and the edges of said flanges when closed being seated against the side flanges of said central member and a flexible connection to both of said cover sections for 100 enabling the latter to be operated laterally in unison.

4. In a device of the character stated, a supporting structure, having side walls, an inclined top and an inclined base member, 115 oppositely located inclined pintles having their upper ends passing through said inclined top and their lower ends positioned within said base member, said pintles inclining outwardly and upwardly from the 120 vertical, a pair of laterally swinging cover sections mounted at their outer ends to turn laterally on said inclined pintles, the inner terminal edge of each cover section having an inturned flange, an outwardly inclined T-shaped member, centrally located between 125 said pintles, and having the same degree of inclination as said pintles, the central web

of said member being parallel to said in-turned flanges, when said cover sections are closed, and the edges of said flanges when closed being seated against the side flanges of said central member, a flexible connection to both of said cover sections for enabling the latter to be operated laterally in unison and a fusible link in said connection, located between the end thereof and said pair

of covers for enabling the latter to swing laterally to open position.

In testimony whereof, I have hereunto signed my name.

ARTHUR R. KONSALIK.
